UNITED STATES PATENT OFFICE.

FRANCIS A. JIMERSON, OF ATHENS, PENNSYLVANIA, ASSIGNOR TO INGERSOLL-RAND COMPANY, OF JERSEY CITY, NEW JERSEY, A CORPORATION OF NEW JERSEY.

REVERSIBLE THROTTLE HANDLE.

Application filed May 12, 1925. Serial No. 29,683.

To all whom it may concern:

Be it known that I, FRANCIS A. JIMERSON, a citizen of the United States, and a resident of Athens, in the county of Bradford 5 and State of Pennsylvania, have invented a certain Reversible Throttle Handle, of which the following is a specification, accompanied by drawings.

This invention relates to fluid actuated rotary tools, such as rotary drills and the like, but more particularly to a reversible throttle handle for machines of this type, in which the reversing valve for the machine is located inside the handle itself. A somewhat similar machine is disclosed in my copending application Serial No. 20,060 filed May 9, 1925, in which the reversing valve is, however, located outside the handle, and operatively connected to be actuated by movement of the handle sleeve. The handle valve of the present application may also be applied to the machine in my copending application Serial No. 29,061 filed May 9, 1925.

The objects of the present invention are to enable the throttle valve and reversing valve to both be located inside the handle and operatively connected, so that the throttle valve has a neutral position to which it automatically returns when the handle sleeve is released, and said valve must pass through neutral position upon reversing rotation of the motor.

The invention is shown in one of its preferred forms in the accompanying drawings, in which—

Figure 1 is a longitudinal sectional view of a rotary drill having my improved throttle handle applied thereto with the throttle valve in closed or neutral position.

Figure 2 is a detail longitudinal sectional view taken through a portion of the handle in a plane at right angles to the plane of the section of Figure 1 showing the throttle valve open, and

Figure 3 is a detail view of a portion of the handle partly broken away and in longitudinal section showing the handle cam.

Referring to the drawings, the case A is provided with an enlarged chamber B at its rearward portion within which the cylinders extend, of which there are three in the present instance, only two cylinders C and D being shown in Figure 1 owing to the longitudinal section on which the drawing is

made, as will be understood. There may of course be any desired number of these cylinders arranged singly or in pairs, but three angularly disposed cylinders will be sufficient for purposes of illustration. The cylinders in this instance are single acting and are preferably removably connected to the case A in any suitable or desired manner as by means of cylinder cap screws (not shown). The pistons F reciprocating in the cylinder are provided with suitable connecting rods G suitably connected to a common crank pin H on a longitudinally extending crank J operatively connected in this instance by gearing at the front end of the machine to drive the rotary drill bit K carried in the spindle L. The pinion E on the forward end of the crank J meshes with the gear O on the spindle L as shown for driving purposes.

The supply of pressure fluid to the machine in accordance with this invention is controlled by a rotatable handle sleeve P connected to actuate the throttle valve P' and also the reversing valve Q both of which are located inside the handle body R, which is connected to the case A as by means of a threaded sleeve S'.

The reversing valve Q, as shown, is provided with the ports S and T and passages U for pressure fluid whereby the passages V and W in the case A may alternately be made supply or exhaust passages, according to the direction in which the motor is intended to rotate the crank J.

In the position of the ports shown in Figure 1, the throttle valve P' is closed but when the valve is opened, as in Figure 2, the pressure fluid supply enters the inlet X at the outer end of the handle body and passes to the machine through the passage V, while the exhaust passes out through the passage W to the port Y and thence to atmosphere. When the valve Q is reversed, the passage W becomes the supply port for the machine and the exhaust passes out through the passage V to the exhaust port Y.

The machine is also provided with a supplemental or auxiliary constantly open exhaust port a except as controlled by the cooperating portion of the crank J which acts as a rotary valve but as this auxiliary exhaust port forms no part of the present invention, its function will not be further

described, said invention and the mode of operation of the rotary valve having been fully described in my said copending application Serial No. 29,061, filed May 9, 1925. 5 The case A is formed with the reduced bore b in which is located the stationary valve bushing c having suitable ports and passages controlled by cooperating ports in the rotation crank J for distributing the pressure fluid to and from the cylinder both on direct and reverse rotation of the motor.

The throttle valve P' is pressed to its seat by means of a valve spring d and an additional lighter conically wound spring e is 15 located around the valve stem f and between the throttle valve P' and the sholuder e' on the handle body R beneath the reversing valve Q. The valve stem f extends into a socket g in the reversing valve and has a 20 slight play therein. The reversing valve is bodily movable longitudinally in the handle body R and is provided with a pin and roller h extending through a cam slot j formed in the wall of the handle body R. 25 The head k of the pin is located in the longitudinal slot o in the wall of the handle sleeve P. The cam slot j in the handle body R is of angular shape and substantially symmetrical so that as the handle sleeve is turned or 30 rotated in one direction or the other, the longitudinal slot o forces the pin h along one inclined side or the other of the cam slot j thus moving the reversing valve Q longitudinally and pushing the throttle valve P' longitudinally to open the valve. 35 Upon releasing the handle sleeve, the pin h automatically returns to the apex of the cam slot j thus returning the throttle valve P' to neutral or closed position. If desired, 40 means may be provided as for instance a notch at the top of the cam slot j to hold the throttle open and to prevent the automatic return to neutral or closed position.

The cam slot j is also preferably deepened 45 at the bottom as shown to produce a distinct or semi-positive neutral position. When the handle sleeve P is rotated, the pin h must first lift out of the depression at bottom of cam slot j bringing the reversing valve Q 50 in operative contact with the end of poppet valve stem f so that further movement then lifts the poppet valve P'. A further object of the lost motion connection between the poppet valve stem f and reversing valve 55 Q is to permit the reversing ports to be appreciably opened before the motive fluid is admitted to the motor.

The depth of the depression in the bottom 60 of the cam slot j is such that an appreciable effort is required to turn the throttle from this neutral position. In operation, the throttle is first turned sufficiently to lift the cam roller h out of this depression before the reversing valve Q moves endwise a sufficient 65 distance to lift the poppet valve P'.

I claim:

1. In a fluid actuated rotary tool, the combination of a case and motor, a handle body, a rotatable handle sleeve, a spring pressed throttle valve and a reversing valve 70 in the handle body, operative connections between the sleeve and the reversing valve, means for actuating the throttle valve by movement of the reversing valve including means for automatically returning the 75 throttle valve to neutral or closed position when the handle sleeve is released after rotation on either direction from neutral position.

2. In a fluid actuated rotary tool, the combination of a case and motor, a handle body, a rotatable handle sleeve, a spring pressed throttle valve and a reversing valve in the handle body, operative connections between the sleeve and the reversing valve, and a 80 cam for causing longitudinal movement of the reversing valve as it is rotated, and thereby actuating the throttle valve.

3. In a fluid actuated rotary tool, the combination of a case and motor, a handle body, a rotatable handle sleeve, a spring pressed throttle valve and a reversing valve in the handle body, operative connections between the sleeve and the reversing valve, a cam for 90 causing longitudinal movement of the reversing valve as it is rotated, and thereby actuating the throttle valve, said cam having oppositely inclined surfaces for causing the throttle valve to return to neutral position when the handle sleeve is released after 95 rotation in either direction from neutral position.

4. In a fluid actuated rotary tool, the combination of a case and motor, a handle body, a rotatable handle sleeve, a spring pressed throttle valve and a reversing valve in the handle body, means for actuating the throttle valve by movement of the reversing valve, a V-shaped cam in the handle body, a pin 105 carried by the reversing valve and forming a follower for the cam, and a slot in the handle sleeve into which the pin extends, whereby rotation of the handle sleeve in either direction from neutral position operates both valves and the throttle valve is 110 automatically returned to neutral or closed position upon release of the handle sleeve 115 after such rotation.

5. In a fluid actuated rotary tool, the combination of a case and motor, a handle body, a rotatable handle sleeve, a spring pressed throttle valve and a reversing valve in the handle body, a lost motion connection for actuating the throttle valve by movement of the reversing valve, a cam slot in the handle body having a depression at its bottom, a follower carried by the reversing valve and adapted to seat in the depression at the bottom of the cam slot when the reversing valve is in neutral position, and a slot in 120 125 130

the handle sleeve cooperating with the said follower, whereby the rotation of the handle sleeve in either direction from neutral position partially opens the reversing valve before operating the throttle valve.

6. In a fluid actuated rotary tool, the combination of a case and motor, a handle body, a rotatable handle sleeve, a spring pressed throttle valve and a reversing valve in the handle body, a lost motion connection for

actuating the throttle valve by movement of the reversing valve, and means for maintaining the reversing valve in neutral position, whereby rotation of the handle sleeve in either direction from neutral position 15 partially opens the reversing valve before operating the throttle valve.

In testimony whereof, I have signed this specification.

FRANCIS A. JIMERSON.
